Specification for Design.

Patented Oct. 11, 1921.

Application filed April 9, 1921. Serial No. 460,077. Term of patent 7 years.

To all whom it may concern:

Be it known that I, COROL R. BAKER, a citizen of the United States, residing at Akron, in the county of Summit and State of Ohio, have invented a certain new, original, and ornamental Design for a Rubber-Tire Casing, of which the following is a specification, reference being had to the accompanying drawing, forming part thereof.

Figure 1 is a plan view of a portion of a rubber tire casing showing my new design.

Fig. 2 is a section taken on line 2—2 of Fig. 1.

I claim:

The ornamental design for a rubber tire casing, as shown.

In testimony whereof I affix my signature.

COROL R. BAKER.
